UNITED STATES PATENT OFFICE.

JOHN RANK AND HENRY W. RANK, OF MINNEAPOLIS, MINNESOTA.

TRAFFIC SIGNAL.

Application filed April 23, 1926. Serial No. 104,060.

Our invention relates to traffic signals of the "self-righting" type, that is, to signal posts adapted to be set in the street and which, if struck by a vehicle, will yield and move 5 into an approximately horizontal position but will resume upright operative positions when released from the vehicle.

Generally stated, the invention consists of the novel devices and combinations of devices 10 hereinafter described and defined in the claims.

In the accompanying drawings, which illustrate the invention, like characters indicate like parts throughout the several views.

15 Referring to the drawings:

Fig. 1 is a view chiefly in elevation but with some parts in vertical axial section and with some parts broken away, showing the improved signal post operatively applied;

20 Fig. 2 is a section taken on the line 2—2 of Fig. 1;

Fig. 3 is a vertical axial section taken on the line 3—3 of Fig. 1;

25 Fig. 4 is a horizontal section taken on the line 4—4 of Fig. 1; and

Fig. 5 is an enlarged fragmentary section taken through the post on the oblique line 5—5 of Fig. 4, some parts being broken away.

The post illustrated has a rigid body portion arranged to rock on a base support of novel construction and arrangement, and it includes primarily four flat plates 6 in rectangular arrangement. These plates have outturned vertical edge flanges 7 over which, 30 at the four corners, are slid coupling tubes 8 that are slit to embrace the flanged edges of the said plates, as best shown in Figs. 2 and 5. These coupling tubes are preferably covered with heavy layers of rubber 9, vulcanized or otherwise secured thereto and affording shock-absorbing cushions exposed in the four corners of the post. At their lower ends, the four side plates 6 are set into a seat afforded by the rectangular upper edge flange 40 10 of a lower end head 11. This lower head 11 is a cast structure and is formed with an undercut annular bearing ledge 12 and below said ledge with a depending inverted centering cone or boss 13. At their upper ends, the 45 four side plates 6 are set into a seat formed by the depending rectangular flange 14 of an upper head 15, which latter, as shown, is formed integral with a skeleton dome 16 that

affords a housing for a light bulb, such as a bulb used as a pilot signal.

55 The upper and lower heads are clamped to the assembled side plates by nut-equipped tie rods 17 passed through the upper and lower heads and through the coupling tubes 8, as best shown in Figs. 2, 4 and 5. The post, as just described, will be a self-contained structure, but is greatly improved by an internal reinforcement, and this we provide by the use of a skeleton core that affords a combined reinforcement and support for the interior 60 lamps and other internal parts of the post. As shown and preferred, this inner skeleton core is made up of four angle iron corner posts 18 and tie plates 19 riveted, spot-welded or otherwise rigidly secured to the said post 18, so that the skeleton core is a self-contained 65 rigid structure capable of being inserted as an entirety into the post proper, and of being removed as an entirety therefrom, when, of course, either the upper head 15 or the lower 70 head 11 has been removed. This skeleton core has a rectangular horizontal cross section and when placed within the post, the angle iron posts 18 closely fit the four corners of the post and securely hold the side plates 6 properly spaced and cause the post to be greatly 75 reinforced.

80 The post described is mounted to stand normally in a vertical position and, as shown, this is accomplished by providing a seat for the centering cone or boss 13 in a seat plate 20 anchored to the road bed y. This plate 20, immediately surrounding the seat for the centering cone 13, is formed with an up-standing annular fulcrum rib 21^a on which 85 the ledge 12 of the lower head 11 is normally seated. The road bed y, as shown, is a concrete structure and, under all but the marginal portion of the plate 20, is formed with a pit 22 preferably of cylindrical form. This 90 pit 22, as shown, is lined by a cylinder 23 that is preferably a piece of tile pipe around which the cement forming the pit 22 is poured. The numeral 24 indicates a metallic anchoring 95 bar that is imbedded in the bottom of the pit. Long nut-equipped bolts 25 are passed through the anchoring bar 24 and through the opposite sides of the seat plate 20. The 100 numeral 26 indicates a flat metal strip, the ends of which are interposed between the 105 plate 20 and the top of the pit wall and

through the ends of which the anchoring bolts 25 are also passed. The central portion of this strap 26 is depressed so that it will clear the centering cone or boss 13 in all positions of the latter.

For yieldingly holding the post normally in an upright position, a weight 27 is provided and this is attached to the lower end of a cable 28 that is passed upward through 10 a central guide passage in the strap 26, through a central opening 29 in the bottom of the centering cone 13, and provided with a knot head or enlargement 30 that stops against the bottom of said cone. Here it 15 should be noted that the lower head 11 is provided with internal stop lugs or ribs 21 that limit the downward movement of the cage 18-19 within the post, (see particularly Figs. 3 and 5).

20 When the post is struck by an automobile or any other moving object, it will readily yield and may be turned down into a horizontal position, as indicated by dotted lines in Fig. 1, under which movement the weight 27, of course, is raised. Under such movement, the strap 26 affords a guide to hold the cable 28 axially of the pit. Here it is important to note that when the post is oscillated or turned down as just stated, it is not the 25 outer edge of the ledge 12 that affords the fulcrum, but the annular rib 21, which maintains engagement in part with the base of the centering cone 13 and in part with the inner portion of the ledge 12. Thus, it will be 30 noted, by reference to the dotted line position of Fig. 1, that when the said post is turned downward, the ledge 12 is entirely outward of the fulcrum rib 21 and will positively hold the post against axial movements 35 toward the left, for instance, in respect to Fig. 1. This engagement also insures accurate return of the post to its vertical position, the said vertical position being determined by complete engagement of the ledge 40 45 12 with the annular fulcrum lug 21, which latter normally acts simply as a seat for said ledge. The centering cone 13, of course, insures accurate axial alignment of the post with the plate 20 and with the pit. The pit,

or, in the structures illustrated, the lining 23, 50 affords a guide for the weight 27 and prevents the same from being given an oscillatory movement when it is moved upward and downward. We have found that a weight is 55 much better than a spring as a means for yieldingly holding the post in an upright position and for restoring it to an upright position when it has been knocked down and released. The weight acts with more certainty than a spring, but is a little slower in 60 its returning action and better adapts itself to the different shocks and strains and, moreover, is a more reliable, durable and permanent device.

What we claim is:

1. A post of the kind described comprising a plurality of wall-forming plates having flanged edges, slotted joint strips telescoped over the flanged edges of said plates, and heads applied to said plates and rigidly holding the same, the said joint strips being covered with an elastic material serving as a cushion. 65

2. A post of the kind described comprising a plurality of wall-forming plates having flanged edges, slotted joint strips telescoped over the flanged edges of said plates, heads applied to said plates and rigidly holding the same, nut-equipped rods passed within said joint strips and through said heads and 75 clamping the latter to the wall-forming plates. 80

3. A post of the kind described comprising a plurality of wall-forming plates having flanged edges, slotted joint strips telescoped over the flanged edges of said plates, heads applied to said plates and rigidly holding the same, nut-equipped rods passed within said joint strips and through said heads and 85 clamping the latter to the wall-forming plates, said joint strips between said heads being covered with elastic material forming 90 cushions. 95

In testimony whereof we affix our signatures.

JOHN RANK.
HENRY W. RANK.
